VEHICLE ORNAMENT

Harold D. Finley, Genoa, Italy

Application January 16, 1952, Serial No. 18,089

Term of patent 14 years

(Cl. D14—6)

To all whom it may concern:

Be it known that I, Harold D. Finley, a citizen of the United States of America, residing at Genoa, Italy, have invented a new, original, and ornamental Design for a Vehicle Ornament, of which the following is a specification, reference being had to the accompanying drawing, forming a part thereof.

In the drawing:

The drawing has been lined for color.

I claim:

The ornamental design for a vehicle ornament, as shown and described.

HAROLD D. FINLEY.
